WINDING APPARATUS

Edward J. Abbe, Cleveland, Ohio, assignor to The Elwell-Parker Electric Company, Cleveland, Ohio, a corporation of Ohio

Application May 17, 1940, Serial No. 335,797

3 Claims. (Cl. 81—57)

This invention relates, generally as indicated, to winding apparatus and has reference more particularly to a vehicle or truck upon which is mounted a rotating device which is adapted for being coupled to a mechanism for imparting torque thereto. This invention is particularly adapted for opening and closing the bottom doors or gates of railroad cars and the like.

It is well known to those acquainted with the art of opening and closing such gates that the same are controlled by an available end of a horizontal shaft which is disposed below the car. This end is usually provided with coupling means, such as a square or hex configuration, for being coupled to and manipulated by a suitable tool such as a wrench and the like. Rotation of the shaft actuates mechanism which opens and closes the gates. Since railroad cars, even of similar type, are not duplicates the position of the end of this shaft will vary from car to car. The relation between the level of the ground and the level of the track varies even though relatively short distances along the track be considered.

The method heretofore employed for opening and closing the gates usually required two men and the use of a wrench, usually of a special ratchet type, provided with a 48 inch lever arm. This method of closing the gates obviously required a considerable period of time for each car.

Where such cars are handled in large numbers, it is conventional for the contents thereof to fall directly into a large bin or other temporary container. In order to accomplish this the cars are positioned on an elevated track over the bin. A cat-walk adjacent the track accommodates gate opening workmen.

By means of this invention, power driven apparatus is provided to replace the manual energy required for opening and closing the gates.

The primary object of this invention has been to provide a quickly maneuverable truck embodying power driven apparatus for opening and closing the bottom gates of railroad cars.

Another object of this invention has been to provide winding apparatus of the type referred to which is adapted to be raised and lowered.

Still another object of this invention has been to provide a device of the character referred to which is equipped with self-locking steering mechanism.

A further object of this invention has been to provide a truck of the character described which is compact and which has incorporated therein safety features.

To the accomplishment of the foregoing and related ends, said invention, then, consists of the means hereinafter fully described and particularly pointed out in the claims; the annexed drawings and the following description setting

forth in detail certain means and one mode of carrying out the invention, such disclosed means and mode illustrating, however, but one way in which the principle of the invention may be used.

5 In said annexed drawings:

Fig. 1 is a side elevation of a device embodying this invention;

Fig. 2 is a plan view thereof;

Fig. 3 is a section taken on the line 3—3 of

10 Fig. 1;

Fig. 4 is a section taken on the line 4—4 of Fig. 3;

Fig. 5 is a section taken on the line 5—5 of Fig. 2;

Fig. 6 is a section taken on the line 6—6 of Fig. 5;

Fig. 7 is a view taken from the left of Fig. 3 with certain elements removed for the sake of clarity;

20 Fig. 8 is a partially fragmentary view taken from the right of Fig. 3;

Figs. 9 and 10 diagrammatically show steering means which are part of this invention;

Fig. 11 is an enlarged section taken on the line 11—11 of Fig. 3 and;

Fig. 12 is an enlarged section taken on the line 12—12 of Fig. 9.

As is above indicated, this invention comprises, broadly, a power-driven truck and a power-driven rotatable coupling mounted thereon. The truck is best seen in Figs. 1 and 2 and will now be described.

The truck in general comprises a heavy frame 15 upon which is mounted within a hood 16 a suitable source of power, such as a motor-generator set for propelling rear wheels 17. Front wheels 18 are adapted for steering and are controlled by steering mechanism which is seen in detail in Figs. 9 and 10 as will hereinafter more fully appear. A platform 20 for supporting the operator of the truck and a plate 22 for guarding and protecting the operator are provided. Where an internal combustion engine is utilized as said source of power, a muffler 25 is provided.

45 Mechanisms for controlling the speed and direction of travel of the truck are mounted upon a suitable control panel 24 and will not be further described since the details thereof are not a substantial feature of this invention.

It is to be noted that the corners of the frame, of the platform and of the plate 22 are smoothly curved and free from overhanging projections such as might engage obstructions during the 55 course of operation of the truck. The hood 16 is provided at the front and rear thereof with ventilating fins 27 which do not overhang the edges of the frame.

The steering mechanism will now be described in detail, reference being had to Figs. 1, 9, 10,

and 12. As is heretofore indicated, the truck will frequently operate upon an elevated cat-walk below which the storage bins are disposed. Where the cargo is ore or coal, it might contain hard lumps which will find their way to the cat-walk. The truck during the course of its travel might be upset or swerve off of the cat-walk by engagement of the front wheels 18 with such lumps. However, if the steering mechanism were of the self-locking type so that it were non-responsive to jolts of the steered wheels, then the possibility of accidentally running off of the cat-walk would be materially reduced.

The steering mechanism is arranged to have such a self-locking means and is controlled by a steering wheel 30 which is preferably horizontally disposed in advance of the control panel 24 as is more clearly seen in Fig. 1. Suitably connected to the steering wheel as by means of a key 32 and nut 33 is a subshaft 34 which is journaled in a block 36. This block is seen in detail in Fig. 12 and comprises a body portion from which projects a pair of pivot arms 38. These arms are supported by the frame immediately below the steering wheel for pivotal movement about a horizontal axis which is perpendicular to Figs. 1 and 9.

The lower end of the subshaft projects within and is welded at 39, or otherwise suitably secured, to a tube 41. This tube is provided with interior threads 42 which engage an exteriorly threaded sleeve 44 which, along with tube 41, projects within and is secured to a sleeve 46 by means of screws 47. Rivets 48 are provided for further securing the tube to sleeve 44. Projecting within the tube and the sleeve 44 is a threaded non-rotatable shaft 50, the threads of which engage interior threads of the sleeve 44.

For the admission of a lubricant for lubricating the threads an opening 51, adapted to be suitably plugged, is provided in the upper portion of the tube, and sealing means 52 prevent loss of such lubricant.

For translating the vertical movement of shaft 50 into horizontal movement, the same actuates a bell crank 55. The bell crank is journaled to the frame 15 by means of an anti-friction bearing 56, the axis of which is parallel to the axis about which the block 36 pivots. One arm of the bell crank is pivotally connected at 57 to a stub shaft 58 which is welded to the shaft 50. A steering reach 60 is pivotally connected to the other end 61 of the bell crank and extends therefrom below the axis of the wheels 17 forwardly to the front wheels 18 where it is pivotally connected to a shearing knuckle 64. The latter is secured by nut 65 to a suitable portion 66 of one of the front axles. Each of the front axles is by means of elements similar to elements 65 and 66 connected to a steering knuckle 68. These steering knuckles 68, are pivotally connected to a radius rod 69.

From the foregoing it will be seen that rotation of the steering wheel 30 rotates the sleeve 44 about the shaft 50. Thus the shaft 50 is raised or lowered with respect to the block 36 or frame 15 and by means of the bell crank pushes or pulls the steering reach and manipulates the individual front axles. It will also be seen that jars imparted to the steering knuckles by means of the front wheels coming in contact with lumps of the character described will not be transmitted as rotational energy to the steering wheel and cause the truck to swerve off the cat-walk. In other words the steering mechanism can be appropriately described as self-locking or irreversible. It

will be further seen that as the shaft 50 is actuated the volume within the tube will vary. For accommodating this variation, a vent 71 is provided in the subshaft 34 and communicates with the interior of the tube by an axial bore 12. Attention is directed to two important instant centers of the steering column. The instant center of the steering column with respect to the frame 15 is stationary and is the axis of the pivot arms 38. The instant center of the steering column with respect to the bell crank 55 is at 57. Thus when the steering wheel 30 is actuated, the whole steering column simultaneously pivots about the bell crank and the frame.

The rotatable coupling for engaging the gate actuating shaft is mounted upon the truck in such manner as to facilitate the proper positioning thereof and will now be described in detail. The coupling as distinguished from the power means for driving the same, will be described first, reference being had particularly to Figs. 5 and 6. The coupling is in the nature of a wrench which is the driven member of a universal joint. The driving member of the universal joint is a square bar 75 which is provided with an enlarged bored end 76. The driven member, indicated generally by 78, is provided at one end thereof with an axial bore 79 and at the other end thereof with a square recess 80 which intersects the bore 79. The square recess 80 may be hex or any other configuration so as to permit it to be coupled to the railroad car bottom gate actuating shaft.

For interconnecting the driving and the driven members there is projecting into the bore 79 and the bore of the end 76 an element 82 which, it is to be noted, is of circular transverse cross section and presents a pair of high spots, one disposed within each of the bores and one of which is indicated at 83. These high spots may, in longitudinal cross section, be V or U shape. Thus the element 82 in longitudinal cross section is in effect substantially a W. As is seen in Fig. 6, the element 82 has extending therethrough a pin 84 the ends of which occupy circumferential extending slots 85 of the end 76. A similar pin 84a and slot 85a interconnect the element 82 and the driven element 78. Pin 84 is disposed at right angles to pin 84a and for permitting play, the slots are longer than the transverse dimensions of the pins. Hence, the driven element 78 may be rotated a limited amount in either direction without disturbing the square bar 75. The configuration of the element 82 permits it to pivot with respect to the square bar about the axis of the interconnecting pin 84 and with respect to the driven element 78 about the axis of interconnecting pin 84a.

Thus the driven element 78 and the square shaft 75 are interconnected for the transmission of rotational energy even though they are swung out of alignment. This universal joint, permitting as is above noted, a limited amount of rotational play between and non-alignment of the driven element 78 and the square bar 75, is useful in coupling the driven element 78 to the gate actuating shaft and eliminates undesirable inching of the truck for aligning the recess 80 with the gate actuating shaft.

For purposes of preventing injury to the fingers of the operator, a suitable, flexible jacket 87 made of rubber for instance, is provided and covers the entire universal joint.

As is above said, the coupling is power driven. The power drive, however, not only rotates the coupling but also raises and lowers the same and

will now be described, reference being had more particularly to Figs. 3, 4, 7, 8, and 11. The power drive is, in general, covered by a hood 90 which is disposed between the hood 16 and the instrument panel 24. For raising and lowering the coupling a motor 92 is provided and for rotating the coupling a motor 94 is provided, each of the motors being mounted exteriorly of the hood 90 and being of the reversible and variable speed type.

Framework for supporting the drive is mounted on the truck and a description thereof follows. Suitably secured to the frame 15 in front of the sheet 22 is a pair of uprights 96 and 97 which by means of welding is provided with a cover 98 and for purposes of rigidity a rear upper plate 99. Extending forwardly from the uprights and secured thereto and to the frame is a pair of vertically disposed plates 101 and 102. As is clearly seen in Fig. 8, the motor 92 is mounted upon a plate 103 which is supported by plate 101 and a vertically disposed plate 104. A plate 106 is suitably secured between the uprights adjacent the lower ends thereof and is provided with a pair of spaced openings for accommodating stationary upright guideways 107 each of which is restrained against upward movement by a pin 108. Each of the guideways 107 projects upwardly through the cover 98 and is restrained against downward movement by means of a nut or the like 110. A pair of plates 112 are each provided with a pair of apertures through which the guideways 107 project so that the plates may be guided thereby. The plates 112 are secured to and spaced apart by a pair of brackets 113 and are provided with aligned openings. The upper plate has non-rotatably secured to the bottom thereof a nut 115 which is aligned with the last said openings.

The moving parts supported by the framework just described comprise a vertically disposed drive shaft 117 which projects through said last named aligned openings, is threaded for engagement with the nut 115, and projects through the cover plate 119 where it is journaled in a bearing 118. The drive shaft also projects through the plate 106 which has secured to the upper portion thereof a thrust bearing 119 in which the drive shaft is rotatably journaled.

For driving the drive shaft there is suitably keyed to the lower portion of the drive shaft a pair of friction discs 121. A pulley 122 is freely rotatably journaled on the drive shaft between the friction discs and is driven by suitable means such as belt 123 and a pulley 124, the latter being driven by the motor 92. For preventing jamming, the friction discs are resiliently urged into engagement with the pulley 122, so as to drivingly connect this pulley and the drive shaft, by a spring 126, the compression of which is adjusted by a washer and nut 128, the latter being threaded to the lowermost portion of the drive shaft.

It is thus seen that when a predetermined amount of torque, transmitted from the motor 92 to the drive shaft, is exceeded that the pulley 122 slips between the friction discs 121 because the normal force exerted by the spring 126 is predetermined. This slipping eliminates any necessity for means responsive to a predetermined elevation of the plates 112 for terminating continued transmission of torque to the drive shaft. It will be seen that, depending on the direction of rotation of the drive shaft that the plates 112 and brackets 113 will be raised or lowered and consequently as will hereinafter appear, the coupling seen in Fig. 5 will be raised or lowered.

Means for rotating the coupling is better seen

in Figs. 3, 4, and 11, wherein the brackets 113 extend forwardly for rotatably and longitudinally slidably supporting the square bar 75. A pair of plates 130 are each secured to the forward ends 5 of the brackets. Each of the brackets and its associated plate is provided with aligned conical openings, the bases of which are adjacent each other for accommodating a Babbitt bearing 131. The rearward ends 134 of a pair of spacer arms 135, which will be hereinafter more fully described, rock with respect to and extend somewhat beyond the forward ends of brackets 113 and are each provided with an opening which is coaxial with the Babbitt bearings 131. Secured 10 to each of the ends 134, as by welding, and extending through and beyond either side of the opening thereof is a sleeve 136 which is rotatably journaled in the Babbitt bearing 131 for accommodating the rocking of the spacer arms with respect to the brackets. Each of the sleeves 136 is provided with a bearing insert 140 of babbitt or the like for rotatably journaling a sleeve-like pair of elements 141.

These elements are each provided with an annular flange 143 which are suitably secured to each other and to a sprocket wheel 144. The remote ends of each of these elements are provided with frusto-conical bores 146 and the adjacent ends thereof are provided with spherical surfaces 148. A sleeve-like swivel block 150, the outer surface of which is spherical, is journaled to the surfaces 148 so that the swivel block may pivot with respect to the elements 141 about a plurality of axes. The adjacent radial faces of the flanges 143 are plane surfaces and for lubricating the spherical surfaces the elements 141 are provided with an annular lubricant groove 152 to which lubricant is supplied by a threaded opening 153, the latter being adapted to be plugged.

For drivingly connecting the swivel block 150 to the elements 141 the swivel block has a keyway 154 and the flanges 143, taken together, are provided with a radially extending bore. Rotatable within this bore is a shank 156 of a T-shaped key. The horizontal portion 157 of this key is provided with a spherical surface 158 conforming to and bearing against the spherical surface 148 so that the key is freely rotatable about the axis of the shank thereof. The horizontal portion is also provided with an arcuate surface 159 so that the swivel block 150 may pivot not only about the axis of the shank 156, but also about an axis perpendicular to the Fig. 11.

The swivel block 150 is further provided with a square axial opening for longitudinally slidably accommodating the square bar 75, the sliding fit being such that the square bar is manually slidable. From the above it will be seen that swiveling of the swivel block is normally limited by the conical surfaces 146 which engage the square bar.

Power means for driving the sprocket wheel 144 and consequently for winding or rotating the coupling means will now be described. Rotatably journaled in the plates 101 and 102 is a driving shaft 160 which by means of a suitable speed reducing unit 161 is driven by the motor 94. Keyed to the driving shaft is a sprocket wheel 163 which by a sprocket chain 164 drives a sprocket wheel 166. Sprocket wheel 166 and a sprocket wheel 168 are each keyed to a shaft 170 and a sprocket chain 171 interconnects sprocket wheels 168 and 144. The said spacer arms 135 have the forward ends thereof rotatably secured to the shaft 170 so as to space the latter from the

axis of the sprocket wheel 144. Rotatably journaled at one end to the shaft 160 and at the other end to the shaft 170 are a pair of spacer arms 172. Shaft 170 is provided at one end with a flange 173 and at the other end with a washer and nut 174 for maintaining in assembled relation the various elements which are supported thereby. It is thus seen that as the driving shaft 160 rotates, the brackets 113, the spacer arms 135 and 172 all pivot relatively to each other. It will also be seen that regardless of the elevation of the square bar 15, the same may be rotated.

The hood 90 is provided with a pair of vertically extending slots 176 for accommodating the square bar.

Space is provided adjacent the hood 16 for accommodating a suitable source of electrical energy such as batteries 180 which start the motor-generator set. By means of a switch lever 181 the speed and direction of motor 94 may be varied. A switch lever 182 adjacent the switch 181 similarly controls the direction and speed of the motor 92.

Operation

Suitable controls (not shown) permit the engine within the hood to propel the truck at various speeds forwardly or rearwardly. By manipulation of the steering wheel 30 the truck is steered so that the coupling element is in the immediate vicinity of the end of the gate actuating shaft. The switch 182 is utilized for raising or lowering the coupling to the same level as the gate actuating shaft. The operator while standing on the platform 20 reaches over the plate 22, grabs the jacket 87 and manually longitudinally moves the square bar until by means of the play hereinbefore described the driven element 18 of the coupling is coupled to the gate actuating shaft. Then by manipulation of the switch lever 181 the motor 94 rotates the square shaft and consequently the gate actuating shaft in one direction or another for opening or closing such gates. After the gates are opened or closed the coupling is disconnected and the truck propelled to the next car.

When the gate actuating shaft is on the side of the truck which is opposite from that seen in Fig. 1, the square shaft is completely withdrawn and inserted from the top of Fig. 2 so as to properly present the coupling.

By the swiveling means best shown in Fig. 11 and the universal joint best shown in Fig. 5, the square shaft need not be perfectly aligned with the said gate actuating shaft.

The plate 22 is provided along the upper edge thereof with a sponge rubber padding 185 for safety purposes.

From the foregoing it will be seen that within predetermined limits regardless of the disposition of the railroad gate actuating shaft, the same may be actuated by the means herein disclosed. It will also be seen that the steering mechanism is non-responsive to jarring of the wheels 18 so that the truck will not swerve off of the cat-walk. The rounding of the corners and general streamlining render the device less likely to engage obstructions so that the same may be operated in relatively close quarters.

Great torque is frequently required to rotate the gate actuating shaft because the gate actuating mechanism is deteriorated or slightly jammed or because of adverse atmospheric conditions. Due to the combined weight of the truck and

power drive coupling, sufficient torque is available without tipping.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:

1. In a device of the character described, the combination of a truck, an elevator, rotatable coupling means, said coupling means being carried by rotatable means horizontally movable relative to said truck and elevator, said rotatable means mounted on said elevator for vertical movement relative to said truck, means for raising and lowering said elevator, means for confining the movement of the elevator substantially to a vertical plane, a driving shaft positioned in a plane parallel to the plane of movement of said elevator at an elevation beyond the range of movement of said elevator, a pair of pivotally connected link members, pivotally connecting respectively to the drive shaft and said rotatable means, and power transmission means interconnecting said drive shaft, the pivotal connection between said link members and said rotatable means whereby rotational movement from the drive shaft may be imparted to said rotatable means throughout the range of movement of said elevator.
2. The combination of a truck, an elevator carried thereby comprising an elevating screw and elevator platform on said screw, means for rotating said elevator screw, coupling means, rotatable means carrying said coupling means, said rotatable means journaled in said elevator platform, a spacer arm pivotally carried by said rotatable means, another spacer arm, a shaft pivotally interconnecting said spacer arms, a driving shaft carried by said last-named spacer arm and positive driving means interconnecting said rotatable means to said shaft and said driving shaft whereby torque is transmitted from said driving shaft to said rotatable means regardless of the height of said elevator.

3. In a device of the character described, the combination of a truck, an elevator comprising a vertical screw, an elevator platform driven by said screw, a pair of friction driving discs for driving said screw, said friction driving discs slipping relatively to each other when the limit of travel of said elevator is reached; coupling means; a universal swiveling driving connection comprising a rotatable hollow sleeve journaled in said elevator platform transversely of said truck, said hollow sleeve having a portion of its interior surface of a spherical form, a second hollow sleeve within said first-named sleeve having external spherical surfaces conforming to the spherical internal surface of said first hollow sleeve and an elongated shaft extending through and being co-axially movable relative to said second hollow sleeve, said elongated shaft carrying said coupling means; a spacer arm pivoted on said first-named hollow sleeve, a second spacer arm pivoted on a driving shaft on said truck, a shaft interconnecting said spacer arms and driving means interconnecting said driving shaft, said first-named hollow sleeve, and said last-named shaft.

EDWARD J. ABBE.
